SELECTIVE TEMPERATURE WATER DISPENSING MEANS

Donald F. Weaver, Rte. 1, West Fork, Ark.
Filed Sept. 25, 1964, Ser. No. 399,317
7 Claims. (Cl. 236—12)

This is a continuation-in-part of my co-pending application, Serial No. 249,926 filed January 7, 1963, now abandoned, which is a continuation-in-part of application, Serial No. 53,236 filed August 31, 1960 now abandoned.

This invention relates to a water dispensing system and more particularly to an apparatus for controlling the temperature and volume of the water for shower heads, dish washers, lavatory faucets, and the like.

When cold water is drawn from the cold water line of a water system there is a momentary decrease of cold water pressure and flow at the point of use. The hot water from the hot water heater is normally maintained for a short time at substantially a constant pressure at the point of use thereby the resulting mixture is hotter than desired until the cold water pressure is brought back to its previous level or sufficient time has elapsed for the hot water pressure to drop to that of the cold water. The most vivid example of this problem is when the point of use is in a bath shower and a toilet is flushed drawing cold water from the cold water source.

However, with the use of the water conditioner of this invention there is substantially no noticeable change in water temperature upon drawing cold water from the cold water source which is also connected to the hot water heater. Moreover, when the thermostatically controlled mixing valve is placed in the discharge water line, there is no noticeable fluctuation in the water temperature at the point of use.

Thus the water conditioner and the mixing valve serve to maintain a constant water temperature at the point of use when cold water is drawn from the cold water source common to the hot water heater and other equipment.

Therefore, one of the objects of this invention is to provide an automatic temperature controlling means for water dispensing devices.

A further object of this invention is to provide a selective water temperature dispensing means that has a volume regulating means at the point of water exit.

A still further object of this invention is to provide a selective water temperature and volume control means at more than one location but operating off of the same water supply.

Still further objects of my invention are to provide a selective temperature water dispensing means that is economical in manufacture and durable in use.

Various other objects and advantages will appear from the following description of the several embodiments of the invention, and the novel features will be particularly pointed out hereinafter in connection with the appended claims, and illustrated in the accompanying drawings, in which:

FIG. 1 is an illustrative view of one embodiment of my invention for selectively controlling the temperature and volume of exiting water at a single point of use;

FIG. 2 is a cross-sectional view of the mixing valve used in each of the embodiments of my invention to control the temperature of exiting water;

FIG. 3 is an illustrative view of another embodiment of my invention for selectively controlling the temperature and volume of water at several points of use while using a single source of water supply;

FIG. 4 is a perspective view of the electrical control

2

assembly used to operate the mixing valve assembly and the valve in the outlet conduit;

FIG. 5 is a fragmentary side elevation view of the pressure conditioner unit employed in the water system of FIGS. 1-3;

FIG. 6 is a fragmentary top plan view of the pressure conditioner unit;

FIG. 7 is a cross-sectional view taken along line 7—7 of FIG. 5; and

FIG. 8 is a view similar to FIG. 7 but of an alternate embodiment of the baffle plate in the pressure conditioner unit.

When like elements are used in each of the embodiments, common numerals are used in the drawings.

15 In FIG. 1, a conventional water heater 7 is connected at its lower end by a pipe 11 to a cold water source (not illustrated). A pipe 42 extending from the top of the water heater 7 is connected to the inlet lower side of the chamber in a pressure conditioner unit 1.

20 The outlet side on top of the pressure conditioner unit 1 is connected by a pipe 12 to a mixing valve 9. The mixing valve 9 includes a housing 10 which has a conduit 11 in communication with the source of cold water, and the conduit 12 in communication with a source of hot water 25 through the unit 1, and an outlet conduit 13 extends from the housing to a point of use, a shower head 15. The volume of water at the shower head is controlled by the solenoid actuated valve 28 in the outlet conduit 13.

Referring to FIG. 2 it can be seen that the housing 10 30 includes a passageway 16 connecting the cold water inlet and the outlet conduit 13. To control the water in this passageway, an ordinary solenoid actuated valve 17 has been inserted. A second passageway 19 in the housing connects the hot water inlet to the outlet conduit 13. In 35 this passageway is a solenoid valve 20. A third passageway 22 in the housing 10 connects the mixing chamber 21 with the outlet conduit 13. The mixing chamber 21 includes an ordinary thermostatic controlled valve 35 between the hot water inlet and the cold water inlet.

40 Referring again to the embodiment in FIG. 1, it can be seen that the hot water from conduit 12 passes through the pressure conditioner unit 1 which is connected to a conventional hot water heater 7 by pipe 42 and the cold water conduit 11 is connected to a source of cold water at the cold water connection on the water heater.

The pressure conditioner 1' is shown in FIGS. 5-8 in a modified form from that used in the system of FIG. 2 since unit 1' is designed to be connected to a plurality of mixing valves 9 such as the two mixing valves shown connected to the unit 1" in FIG. 3.

50 The unit 1' of FIGS. 5-7 includes an elongated cylindrical in cross-section tank 70 having a chamber 72 formed therein. The tank 70 is horizontally disposed and is provided with an inlet opening 74 connected to the pipe 42 extending to the outlet top end of the water heater 7. A pair of outlet openings 76 are provided in the top wall of the tank 70 and have pipes 12 extending therefrom for connection to a mixing valve 9. Also, outlet openings 78 are formed in the opposite end wall of the tank 70.

60 Each of the outlet openings 76 and 78 are disposed above a baffle plate 80 extending the length of said tank 70. The flat plate 80 is provided with a plurality of openings 82 through which water passes to reach the outlet openings 76 or 78. The plate 80 is secured by weldments 83 to 65 the side wall of the tank 70.

A modified baffle plate 80' is illustrated in FIG. 8 and differs from that in FIGS. 5-7 by being convex upwardly rather than flat as is plate 80.

70 Certain of the components of the control assembly illustrated in FIG. 4 are schematically represented in FIGS. 1 and 3 by switches 29, 30, 31 and 33 which, respectively,

when moved to a closed position, open the warm water valve 23, the cold water valve 17, the hot water valve 20 and the valve 28 in the outlet conduit 13. The outlet valve 28 is non-closeable and consequently when the switch 33 is open the valve permits a minimum of water to pass. This will indicate to the user of the system that one of the other switches is in a closed position and its respective solenoid valve is energized. When the switch 33 is closed a maximum of water will flow due to the opening of the valve 28 in the outlet conduit 13. Any number of desired water temperatures may be obtained by opening and closing singularly or in combination the switches 29, 30 and 31.

The switches in the control assembly 45 are operated on low voltage power of approximately 12 volts by use of step-down transformers 41 in the temperature switch circuit and the transformer 40 in the outlet conduit valve circuit. Lead-in lines 25 and 26 supply ordinary 110 line voltage. The low voltage across the solenoids will prevent their destruction in the event they remain energized when one or more of the switches are left closed for an extended period of time beyond normal usage. Additionally, the low voltage eliminates the possibility of the user being shocked while in contact with the water at the point of use.

The control assembly 45 additionally includes a signal light for each of the switches to indicate whether the switch is closed. Signal lights 46, 47, 48 and 49 will burn when the respective switches 31, 29, 30 and 33 are closed. The toggles 50, 51, 52 and 53, respectively, operate the switches.

In the embodiment illustrated in FIG. 3 of the drawings, the system of FIG. 1 is duplicated permitting two separate uses of the outlet water from a single source of inlet water, i.e., for a shower 15 and a bath tub 44. To maintain a steady level of hot water flowing to each of the mixing valves 9 when both are in use, the hot water supply conduit 42 has a size of for example $\frac{3}{4}$ inch to $\frac{1}{2}$ inch for the outlet pipes 12 communicating with the mixing valve.

Thus it is seen that the head of water pressure in the heater 7 is rendered ineffective in maintaining a high pressure at the point of use such as the tub 44 or shower 15 when the cold water source pressure is reduced. The pressure at the point of use of the hot water is then substantially equal to the pressure of the cold water and therefore the temperature of the mixture remains constant.

From extended use of the system described, it has been found completely effective and comparable experience with mixing valves alone has proven totally unsatisfactory since the momentary drop in cold water pressure at the point of use is not accomplished by a corresponding reduction in the hot water pressure line and accordingly the temperature at the point of use is for a short, but intolerable period of time, too hot.

It can be appreciated that when the cold water source pressure is reduced such as by flushing a toilet or the like, the cold water pressure will be reduced to the mixing valve 9 as well as to the heater 7. If pressure conditioner 1' were not present, hot water from heater 7 would momentarily be supplied to mixing valve 9 at the same pressure which it previously was being supplied to due to the head of pressure within heater 7. This means that the hot water pressure in mixing valve 9 would be greater than the cold water pressure therein due to the reduction of cold water pressure. This would result in an increase in water temperature at the point of use for a short time. Pressure conditioner 1' momentarily prevents the head of water pressure in heater 7 from reaching mixing valve 9 due to the baffle means therein resisting the surge of hot water. Pressure conditioner 1' momentarily resists the surge of hot water from heater 7 until the reduction in the hot water pressure line is effected. In effect then, pressure conditioner 1' conditions or controls the pressure of the hot water between

heater 7 and mixing valve 9 to prevent the water at the point of use from becoming too hot.

Some changes may be made in the construction and arrangement of my Selective Temperature Water Dispensing Means without departing from the real spirit and purpose of my invention, and it is my intention to cover by my claims, any modified forms of structure or use of mechanical equivalents which may be reasonably included within their scope.

I claim:

1. In a liquid distribution system for supplying thermostatically controlled liquid to a point of use at a consistent pre-selected temperature, comprising,

a source of cold liquid,
a heater container having an inlet and an outlet, a heating means in said container and said cold liquid source being connected to said inlet of said container, a pressure conditioner unit having a chamber formed therein and an inlet opening in communication with said chamber, said unit having an outlet opening in communication with said chamber at a point remote from said inlet opening into said chamber, a baffle means in said chamber between said inlet of said chamber and said outlet of said chamber, a pipe means connecting the inlet of said chamber to the outlet of said heater container, a mixing valve connected by a pipe means to the outlet of said pressure conditioner unit, a conduit connecting said cold liquid source to said mixing valve, said mixing valve having an outlet and means connecting said outlet to the point of use at a discharge station, and

means independent from said heater container and said mixing valve for drawing liquid from said cold liquid source at times and thereby varying the pressure within said heater container.

2. In a liquid distribution system for supplying thermostatically controlled liquid to a point of use at a consistent pre-selected temperature, comprising,

a source of cold liquid,
a heater container having an inlet and an outlet, a heating means in said container and said cold liquid source being connected to said inlet of said container, a pressure conditioner unit having a chamber formed therein and an inlet opening in communication with said chamber, said unit having an outlet opening in communication with said chamber at a point remote from said inlet opening into said chamber, a baffle means in said chamber between said inlet of said chamber and said outlet of said chamber, a pipe means connecting the inlet of said chamber to the outlet of said heater container, said heater container having a capacity substantially greater than the capacity of said chamber in said pressure conditioner, a mixing valve connected by a pipe means to the outlet of said pressure conditioner unit, a conduit connecting said cold liquid source to said mixing valve, said mixing valve having an outlet and means connecting said outlet to the point of use at a discharge station, and

means independent from said heater container and said mixing valve for drawing liquid from said cold liquid source at times and thereby varying the pressure within said heater container.

3. The structure of claim 2 wherein said pressure conditioner unit has a perforated baffle plate disposed in said chamber between said inlet opening and said outlet opening whereby fluid moving from said unit flows through said baffle plate perforations.

4. The structure of claim 2 wherein said pressure conditioner unit is cylindrical in cross-section and elongated with its longitudinal axis being horizontally disposed.

5. In a liquid distribution system for supplying thermostatically controlled liquid to a point of use at a consistent pre-selected temperature, comprising,
 a cold water source,
 an upstanding heater container having an inlet adjacent its lower end and an outlet adjacent its upper end,
 a heating means in said container and said cold water source being connected by a pipe means to said inlet of said heater container,
 a pressure conditioner unit disposed above said heater container, said unit having a chamber formed therein and an inlet opening in communication with said chamber, said unit having an outlet opening in communication with said chamber,
 a baffle means in said chamber between said inlet of said chamber and said outlet of said chamber,
 a pipe means connecting the inlet of said chamber to the outlet of said heater container,
 said heater container having a capacity substantially greater than the capacity of said chamber in said pressure conditioner,
 a mixing valve connected by a pipe means to the outlet of said pressure conditioner unit,
 a conduit connecting said cold liquid source to said mixing valve, said connection to said cold water source being adjacent the pipe connecting said cold water source to said heater container inlet,
 said mixing valve having an outlet and means connecting said outlet to the point of use at a discharge station,

5

10

15

30

means independent of said heater container and said mixing valve for drawing cold water from said cold water source at times and thereby reducing the pressure of said cold water in said cold water source, said heater container inlet and said mixing valve, and thereby at the point of use.

6. The structure of claim 5 wherein said pressure conditioner unit has a flat perforated baffle plate extending lengthwise in said chamber between the inlet and outlet of said unit.

7. The structure of claim 5 wherein said pressure conditioner unit has a convex upwardly in cross-section perforated baffle plate extending lengthwise in said chamber between the inlet and outlet of said unit.
